UNITED STATES PATENT OFFICE

154,058

DESIGN FOR A FLUORESCENT LIGHTING FIXTURE

Carl Nitardy, Ipswich, Mass., assignor to Sylvania
Electric Products Inc., Salem, Mass., a corpora-
tion of Massachusetts

Application September 12, 1947, Serial No. 141,355

Term of patent 14 years

(Cl. D48—23)

To all whom it may concern:

Be it known that I, Carl Nitardy, a citizen of the United States, residing at Ipswich, in the county of Essex and State of Massachusetts, have invented a new, original, and ornamental Design for a Fluorescent Lighting Fixture, of which the following is a specification, reference being had to the accompanying drawing, forming part thereof.

Fig. 1 is a bottom perspective view of a fluorescent lighting fixture showing my new design, and

Fig. 2 is a top perspective view thereof.

I claim:

The ornamental design for a fluorescent lighting fixture, as shown.

CARL NITARDY.
